UNITED STATES PATENT OFFICE

CLARENCE M. ELLENBERGER, OF DETROIT, MICHIGAN, ASSIGNOR, BY MESNE ASSIGNMENTS, TO OAKES PRODUCTS CORPORATION, A CORPORATION OF MICHIGAN

VISE GRIP LOCK

Application filed December 5, 1928. Serial No. 323,975.

This invention relates to vise grip locks of the character adapted to secure in place portable automobile accessories, such as spare tires and the like. More particularly, 5 the invention has to do with the lock structure, whereby a member which is operable by a wrench, may be so positioned as to prevent application of the wrench, and locked in such position.

10 It is an object of the invention to provide an operating member which is movable from an accessible to an inaccessible position, with means to lock it in inaccessible position.

15 A further object of the invention is to provide an operating member presenting a surface flush with the surface of the member in which it is mounted when in locked position, and adapted when unlocked to project therebeyond and afford a non-circular cross section for application of torsional forces.

20 Other objects and features of novelty will be apparent as the following description 25 proceeds, as read in connection with the accompanying drawings, in which:

Fig. 1 is a vertical cross sectional assembly view of a structure constituting one embodiment of the present invention.

30 The remaining figures illustrate details of construction of parts shown in Fig. 1.

Referring more particularly to the drawings for a detailed description of one embodiment of the invention, there is illustrated a vise grip lock, which is adapted to secure in place portable automobile accessories, such as spare tires, and the like. This device comprises generally a main member 10, a movable jaw 11, and a bolt 12.

35 The main member 10 is elongated, generally cylindrical, and provided with a depending flange 13 which constitutes one jaw of the vise. The lower portion of the outer end of the member 10 is cut away as at 14 to receive the jaw 11, leaving an overhanging flange 15 which forms a hood or socket overlying the movable jaw 11. The member 10 is provided with a central bore 16 of substantially uniform diameter except at 40 the inner end thereof, which is of reduced

diameter forming a shoulder 17 which serves to retain the bolt 12. The bolt 12 has a head 18, the bolt and head both being of such diameter that the bolt may be inserted through the bore 16 and pass through the 55 annular shoulder 17 so that the head 18 fits snugly thereagainst.

The bore 16 also receives a cylinder housing 19, the inner end of which is slotted as at 20, this central rectangular slot leaving projecting lugs 21. The bolt head 18 is correspondingly slabbed off as at 22, to mate with the cylinder housing, thus forming a head projection 23 adapted to enter the slot 20, the lugs 21 entering the slabbed 60 off portion 22. The head projection 23 is provided with a central bore 24 which receives a coil compression spring 25. One end of this spring bears against the bottom of the bore 24, and the other end bears 70 against the bottom of the rectangular slot 20 thus exerting an outward pressure on the cylinder housing.

Locking means are provided for retaining the cylinder housing 19 in the bore 16 75 against the action of the spring 25. The cylinder housing is accordingly transversely bored part of the way therethrough as at 26, to receive a lock bolt 27. One end of the lock bolt is drilled as at 28 to receive 80 one end of a coil compression spring 29, the other end of which seats in the bottom of the bore 26, and normally tends to thrust the lock bolt 27 out of the bore 26. The main bore 16 is provided with an annular 85 groove 30, into which the outer end of the lock bolt 27 extends.

The cylinder housing is centrally bored to receive the lock cylinder 31. The inner end of the lock cylinder 31 carries a lug 32, eccentrically mounted thereon and adapted to engage the lock bolt 27 by entering a rectangular slot 33 formed in the side of the bolt 27. In the inner surface of the lock cylinder, starting from a point opposite the lug 32, an 90 arcuate groove is cut which extends 95 degrees around the circumference of the cylinder. This groove 34 is adapted to receive a stop pin 35, so that the lock cylinder may have relative movement with respect to the 100

cylinder housing, which movement is limited to 90 degrees.

The outer end of the cylinder housing is slabbed off as at 36, leaving shoulder 37.

- 5 As there are six slabbed off portions, the outer end of the cylinder housing forms a hexagonal nut. The outer end of the bore 16 is recessed as at 38 and snugly receives a collar 39 having a hexagonal central aperture 40 which fits the hexagonal outer end of the cylinder housing. The collar 39 is retained in the recess 38 by means of the snap ring 41, which will permit rotation but not longitudinal movement of the collar 39
- 10 with respect to the main member 10. A similar snap ring 42 serves to retain the lock cylinder inside the cylinder housing. The lock cylinder 31 is provided with tumblers, etc., so that it may be operated only by the insertion of a key.
- 15

In operation, when the parts are in the locked position and it is desired to remove the tire or other accessory, the key is inserted in the lock cylinder 31 which is revolved 90 degrees, during which the pin 35 rides in the slot 34. At the same time the rounded lower portion of the lug 32 bears on the bottom of the slot 33 in the lock bolt 27 and withdraws it from the annular groove 30 against the action of the spring 29. The bolt 27 is thus retracted into the bore 26, and hence no longer retains the cylinder housing against the action of the spring 25, which forces it outwardly until the shoulder 37 abuts against the inner end of the collar 39. This permits the hexagonal outer end of the cylinder housing to extend outwardly a sufficient distance to permit it to be readily engaged by a wrench. Turning of the cylinder housing by means of a wrench now turns the bolt 12, by reason of the mating of the lugs 19 with the slabbed off projection 23 of the bolt head. The movable jaw 11 being in threaded engagement with the bolt 12 will thus be moved outwardly, and the vise grip provided by the flanges 10 and 11 will thus be released. The entire lock as well as the accessory secured thereby can now be removed.

- 20 To restore the parts, the flanges 10 and 11 are placed on either part of the tire, and by application of the wrench, the bolt 12 can be used to cause the jaws 10 and 11 to exert a vise-like grip on the accessory to be secured.
- 25 The wrench is now removed, and the extended end of the cylinder housing is pushed back against the action of the spring 25, until the outer end of the lock bolt 27 rides into the annular groove 30. The spring 29 will at once force the lock bolt 27 into the groove, and thus retain the cylinder housing in position. It should be noted that the parts are so dimensioned that the outer surface of the cylinder housing is flush with the outer face
- 30 of the member 10. Furthermore, the central

aperture of the collar 39 fits snugly against the sides of the hexagonal portion of the cylinder housing. This arrangement leaves no aperture through which instruments may be inserted to effect the unauthorized opening of the lock.

70 While one embodiment of the invention has been shown and described in comparative detail, the scope of the invention is not limited to any of these details, but includes such embodiments of the broad idea as come within the scope of the appended claim.

75 Having thus described the invention, what I claim is:

80 In a locking device of the class described, the combination of a frame having a bore, a securing member rotatable in said bore, an operating member rotatable in said bore and having its outer end adapted to receive a tool for rotating said operating member, coupling ends on said members adapted to transmit rotation of said operating member to said securing member but to permit axial movement of said operating member relative to said securing member, said coupling ends 85 having communicating pockets, a compression spring confined within said pockets tending to hold said operating member with its tool receiving end outside of said frame for the application of a tool thereto, and means for locking said operating member against the pressure of said spring to retain its tool-receiving end concealed within said frame.

90 100 In testimony whereof I affix my signature.

CLARENCE M. ELLENBERGER.
